(57) CLAIM

The ornamental design for a bottle, as shown and described.

DESCRIPTION

FIG. 1 is a top and right front perspective view of a bottle showing my design;

FIG. 2 is a front elevational view thereof;

FIG. 3 is a right side elevational view thereof, the left side elevational view being a mirror image of the side view shown;

FIG. 4 is a top plan view thereof; and,
FIG. 5 is a bottom plan view thereof.

The phantom line showing of the cap for the bottle in FIGS. 1-5 is for illustrative purposes only and forms no part of the claimed design.

1 Claim, 4 Drawing Sheets
